SICKLE GUARD

Arthur G. Gable, Toledo, Ohio, assignor to Toledo Stamping & Manufacturing Company, Toledo, Ohio, a corporation of Ohio

Application July 2, 1947, Serial No. 758,565

7 Claims. (Cl. 56—311)

1

This invention relates to sickle guards of the type used on horse drawn or power mowers, and more particularly to mower guards made of sheet metal.

Heretofore sickle guards have been made from forgings and castings. These forgings and castings are solid members and are quite heavy. Excess weight is objectionable especially with longer cutter bars coming into use at the present time.

Sickle guards are often subjected to impact and bending stresses. Cast and forged metals have low resistance to impact and bending stresses due to the characteristics of cast and forged metals. In order to obtain the strength required to produce satisfactory cast and forged sickle guards sufficient metal has been put into the sickle guard to give the desired strength. This has resulted in a heavy sickle guard.

My improved sickle guard overcomes this objection in two ways. My improved sickle guard is made from sheet metal which is stronger and more resilient than cast or forged iron. My improved sickle guard has a channel shaped cross section which gives more strength per unit of cross sectional area than does a solid section such as is used in the conventional cast or forged sickle guard.

My improved sickle guard is made of sheet metal formed in stamping processes. The expensive machining processes required on cast and forged sickle guards are eliminated in my improved sickle guard.

One of the objects of my invention is to provide a sickle guard that provides the greatest possible strength per unit weight of material.

Another object of my invention is to provide a sickle guard that eliminates expensive machining processes.

Another object of my invention is to provide a sickle guard with a cross section that provides the maximum strength per unit area of the cross section.

Another object of my invention is to provide a sickle guard that is adapted to quantity production.

Another object of my invention is to provide a sickle guard that is simple, strong, durable, and inexpensive.

With these and other objects in view, my invention consists in the construction, combination, and arrangements of the various parts of my improved device as described in the specification, claimed in the claims and illustrated in the accompanying drawing in which:

2

Figure 1 is a top plan view of my improved sickle guard.

Figure 2 is a side elevation of my improved sickle guard.

Figure 3 is a sectional view taken along line 3—3 of Figure 1.

Figure 4 is a sectional view taken along line 4—4 of Figure 2.

Figure 5 is a sectional view taken along line 5—5 of Figure 2.

Figure 6 is a sectional view taken along line 6—6 of Figure 3.

Figure 7 is a sectional view taken along line 7—7 of Figure 3.

Figure 8 is a sectional view taken along line 8—8 of Figure 3.

Figure 9 is top plan view of the ledger plate used in connection with my improved sickle guard.

20 Referring to the drawings I have shown one form of my invention comprising a lower stamping 10, an upper stamping 11, a ledger plate 12, and a rivet 25.

The lower stamping 10 has a channel shaped body portion 14, a flat tapering nose portion 13 extending forwardly from the channel shaped body portion 14 and a securing portion 15 extending rearwardly from the body portion 14. The securing portion 14 is provided with an aperture 16.

25 When my improved sickle guard is secured to a cutter bar (not shown) a bolt is inserted through the aperture 16 and the sickle guard is bolted to the cutter bar (not shown) with the upper surface 17 of the securing portion 15 against the lower surface of the cutter bar. The flanges 18 protrude from the sides of the securing portion. The flanges 18 abut similar flanges of adjacent sickle guards when the sickle guards are secured on a cutter bar (not shown).

30 40 The abutting flanges 18 of adjacent sickle guards keep the sickle guards properly located on the cutter bar. The body portion 14 is provided with a flat ledger plate bed 19. A ledger plate securing finger 20 extends rearwardly from the forward portion of the channel shaped body portion 14.

The upper stamping 11 is provided with a curved body portion 21. The lower edges of the curved body portion engage the lower channel shaped body portion 14 as shown in Figures 5 and 6. A flat tapering nose portion 22 extends forwardly from the curved body portion 21 adjacent the upper surface of the nose portion 13. A lip or knife guard portion 23 extends rearwardly.

45 55 The ledger plate 12 is provided with a securing

tongue 24. The securing finger 20 and the curved body portion 21 hold the forward end of the ledger plate in position. A rivet 25 secures the rear end of the ledger plate 12 in position.

In the manufacture of my improved sickle guard the upper stamping 11 and the lower stampings are separately formed from individual blanks of predetermined size and shape in a plurality of stamping operations. The lower stamping 10 and the upper stamping 11 are welded together as shown at 26 while they are held in the proper position by a suitable fixture. After the upper stamping 11 and the lower stamping 10 are properly secured together the tongue 24 of the ledger plate 12 is inserted under the securing finger 20 and the side walls of the curved body portion 21. The rivet 25 is then added to keep the ledger plate 12 securely in position.

The upper stamping 11 and the lower stamping 10 can also be secured by a brazing process instead of the welding process described above.

From the preceding description it will be noted that my improved sickle guard is composed of an upper stamping 11, a lower stamping 10, a conventional ledger plate 12 and a rivet 25. As stated above the upper and lower stampings are stamped or pressed from a sheet metal blank. In this stamping or pressing process the fibers of the sheet metal are preserved thus producing a sickle guard which preserves the strength of the sheet metal. The channel shape of the lower body portion 14 also provides maximum strength. From the above description it is evident that my improved mower guard is strong, resilient and light in weight.

While I have described one form of my invention, I do not wish to be limited to the particular form shown and described as it will be apparent to those skilled in the art that many modifications therein may be made without departing from the scope of my invention.

Having thus described my invention, what I claim is:

1. A sickle guard comprising a lower stamping, said lower stamping comprising a downwardly open channel shaped body portion, a flat nose portion extending forwardly therefrom and a securing portion extending rearwardly therefrom; and an upper stamping comprising a curved body portion secured to said channel shaped body portion, a flat nose portion extending forwardly from said curved body portion and secured to first said nose portion thereby providing a solid nose portion and a lip extending rearwardly from said curved body portion above said channel shaped body portion, both of said flat nose portions extending to the forward end of said sickle guard to provide a horizontally laminated flat nose portion.

2. A sickle guard comprising a lower stamping; said lower stamping comprising a downwardly open channel shaped body portion, a flat tapering nose portion extending forwardly from said curved body portion to the foremost portion thereof above said flat tapering portion of said lower stamping and secured thereto thereby providing a solid nose portion, and a lip extending rearwardly from said curved body portion.

3. A sickle guard comprising a lower stamping; said lower stamping comprising a downwardly

open channel shaped body portion, a flat tapering nose portion extending forwardly therefrom, a securing portion extending rearwardly from said body portion and a plurality of flanges extending sidewise from said securing portion adapted to engage similar flanges of adjacent sickle guards; and an upper stamping comprising a convex body portion secured above said channel shaped body portion, a flat tapering nose portion extending forwardly from said convex body portion extending to the foremost portion of and secured to the upper surface of said flat tapering nose portion of said lower stamping to provide a solid nose portion of said sickle guard and a lip portion extending rearwardly from said curved body portion thereby providing a knife slot between said lip and said channel shaped body portion.

4. A sickle guard comprising a lower stamping; 20 said lower stamping comprising a downwardly open channel shaped body portion, said channel shaped portion body providing a flat ledger plate seat, a flat nose portion extending forwardly from said channel shaped body portion, a securing portion 25 of substantial channel shape extending rearwardly from said channel shaped body portion, a plurality of flanges extending sidewise from said securing portion; an upper stamping comprising a convex body portion secured to the forward portion 30 of said channel shaped body portion, a nose portion extending forwardly from said convex body portion above said flat nose portion of said lower stamping and secured thereto thereby providing a horizontally laminated flat nose 35 portion, a lip extending rearwardly from said convex body portion above said ledger plate seat; a ledger plate located on said ledger plate seat and a plurality of means for securing said ledger plate on said ledger plate seat.

5. A sickle guard comprising a lower stamping; said lower stamping comprising a downwardly open channel shaped body portion, a flat tapering nose portion extending forwardly therefrom and a securing portion extending rearwardly 45 from said body portion, a flat ledger plate seat provided by the upper surface of said body portion and a finger member extending rearwardly from said nose portion above the level of said ledger plate seat; an upper stamping comprising a convex body portion secured to the forward portion 50 of said channel shaped body portion, a nose extending forwardly from said convex body portion above said nose portion of said lower stamping and secured thereto, both of said flat nose portions terminating at the same forward point to provide a solid nose portion of said sickle guard, a lip extending rearwardly from said convex body portion above said ledger plate seat; a ledger plate located on said ledger plate seat, the forward end 55 of said ledger plate secured in position by means of said finger member of said lower stamping and the convex body portion of said upper stamping; and a rivet adapted to secure the rear end of said ledger plate in position.

6. A sickle guard comprising a lower stamping; said lower stamping comprising a downwardly open channel shaped body portion, a flat tapering nose portion extending forwardly therefrom, a securing portion extending rearwardly from said body portion, a flat ledger plate seat provided by the upper surface of said body portion and a finger member extending rearwardly from said nose portion above the level of 70 said ledger plate seat; and an upper stamping 75

comprising a convex body portion secured to the forward portion of said channel shaped body portion, a nose portion extending forwardly from said convex body portion above and to the forward portion of said nose portion of said lower stamping and secured thereto to provide a solid nose portion of said sickle guard and a lip extending rearwardly from said convex body portion above said ledger plate seat.

7. A sickle guard comprising a lower stamping; 10 said lower stamping comprising a downwardly open channel shaped body portion, said channel shaped body portion providing a flat ledger plate seat, a flat nose portion extending forwardly from said channel shaped body portion, a channel 15 shaped securing portion extending rearwardly from said channel shaped body portion, and a plurality of flanges extending sidewise from said securing portion, an upper stamping entirely located above said lower stamping, said upper 20 stamping comprising a convex body portion secured to the forward portion of said channel shaped body portion, a flat nose portion extending forwardly from said convex body portion above said flat nose portion of said lower stamp- 25

ing and terminating at the same forward point, both of said flat nose portions co-acting to provide a nose portion of said sickle guard, a lip extending rearwardly from said convex body portion above said ledger plate seat; a ledger plate located on said ledger plate seat and a plurality of means adapted to secure said ledger plate on said ledger plate seat.
